TELEPHONE SYSTEM

John William McClew, Liverpool, England, assignor to Associated Telephone and Telegraph Company, Chicago, Ill., a corporation of Delaware

Application April 26, 1934, Serial No. 722,589
In Great Britain May 2, 1933

8 Claims. (Cl. 179—16)

The present invention relates to telephone or like systems and is more particularly concerned with impulse repeaters for use in such systems which respond to impulses of one type and re-transmit impulses of a different type, for instance which convert alternating current impulses into direct current impulses. The chief object of the invention is the production of an impulse repeater suitable for terminating a phantomed junction line which shall respond to alternating current impulses of commercial frequency and re-transmit impulses suitable for operating automatic switches and also impulses for effecting control operations such as trunk offering.

According to one feature of the invention in an impulse repeater for use in telephone or like systems incoming impulses of one type are adapted to be converted into impulses of a different type the character of which varies dependent on the number of trains of impulses which have been transmitted to the repeater independently of the length of individual incoming impulses.

According to another feature of the invention in an impulse repeater for use in telephone or like systems incoming impulses of alternating current are converted into impulses of direct current differing in character for different trains of impulses independently of the length of individual incoming impulses and independently of any signal received from other equipment.

With reference to the expression "train of impulses", it should be explained that an impulse is considered to belong to a fresh train of impulses if a certain minimum period has elapsed since the sending of the preceding impulse and from this it follows that a train may consist of only one impulse.

The invention will be better understood from the following description of one method of carrying it into effect, reference being had to the accompanying drawings comprising Figs. 1 and 2 which should be arranged side by side to form a complete circuit.

Considering now the detailed circuit operation, when the impulse repeater shown is taken into use over the junction line conductors 10 and 11, a preliminary seizing pulse of alternating current of commercial frequency is extended forward over the junction from the distant office and is repeated by induction over the repeating coil RPC to operate the alternating current relay AC which may be suitably tuned or may be an ordinary direct current relay shunted by a dry rectifier. The phantom circuit tapping from the repeating

coil RPC is shown extending from the centre point of the left-hand winding. Relay AC operates relay A and this in turn energizes relay B. Relay B thereupon locks by way of its armature *b*1, and at armatures *b*2 and *b*3 prepares the loop circuit for the incoming selector which includes the winding of the impedance I connected in series with the line winding of the shunt field relay D. At the end of the preliminary seizing pulse, relays AC and A restore but relay B remains operated through armature *b*1 so as to enable armature *a*2 to complete the operating circuit to the incoming selector, which selector thereupon connects guarding earth potential to the release trunk conductor P.

Upon the reception of the first series of setting impulses which are similar to the seizing impulse, relay AC responds and as before operates relay A, which at armature *a*2 repeats these impulses in the form of interruptions in a direct current loop circuit which serve to set the incoming selector wipers to the required level. Relay C operates through armature *a*3 with the first pulse, and by reason of its slug and the intermittent energization of its windings remains held throughout the impulsive period, thereby at armatures *c*2 and *c*3 disconnecting the calling side of the transmission circuit to prevent distortion of the impulses and at the same time short circuiting the impedance I and the control winding of relay D to provide a more effective impulsive circuit for the incoming selector. Relay C moreover energizes the driving magnet SPM of the rotary switch which advances its wiper SPB into position 2. It should be explained that the rotary switch is very small and economical to manufacture and comprises essentially a coil similar to an ordinary telephone relay, which in addition to the usual sets of contact springs is provided with a forward drive pawl and ratchet mechanism which rotates a shaft carrying the wiper SPB.

Armature *a*1 short circuits relay B through the operated armature *c*6 each time relay A responds to an impulse, but relay B remains operated during impulsive because of the momentary nature of the individual impulses.

Subsequent series of impulses are transmitted in the manner described and at the beginning of each separate train the wiper of the rotary switch is advanced one step owing to the operation of relay C. The circuit as shown is arranged for the repetition of five trains of impulses, at which time the wiper SPB comes into its 6th position, in which relay DC is operated on the release of re-

lay C. Relay DC locks up at armature *dc1* and at armature *dc2* prepares a leg impulsive circuit suitable for transmitting signals for effecting for example cut in on busy connections, toll breakdown and re-ring.

If the junction has been taken into use by a toll operator and the called line proves busy, it may be desirable for the operator to cut in on the busy connection in order to offer the long distance 10 call. This is done by the transmission of a further impulse of alternating current over the junction which causes the operation of relays AC and A in the manner previously described. Since relay DC is now operated however, an earth impulse 15 is transmitted over the negative line extending to the automatic train of switches which serves to operate a differential relay in the controlling switch in the train in order to set up the cut-in facility. Toll breakdown and re-ring 20 are effected by the extension of further impulses of alternating current over the junction, and for each impulse received the repeater connects earth to the negative line so as to operate the differential relay in the controlling switch in the train.

If the wanted subscriber is idle, when he replies battery is reversed back over the train of 25 automatic switches and this brings about the operation of the shunt field relay D which at armature *d1* operates relay E over its upper winding. Thereupon at armature *e3* a circuit is completed 30 for the slow-to-operate relay DR which in due course opens the circuit of relay E at armature *dr1*. During the slow operating time of relay DR, however, an alternating current impulse 35 connected to the junction over armature *e1* and *e2* and this provides answering supervision for the operator, or alternatively brings about the operation of the calling subscriber's meter in the case of an auto-to-auto connection.

If the called subscriber wishes to attract the attention of the operator he may do so by flicking his switch-hook which results in the intermittent de-energization of relay D. Relay E is 40 momentarily operated over its lower winding when relay D releases, pending the restoration of timing relay DR, and is again momentarily operated as explained when relay D reoperates, so that impulses of alternating current are connected to the junction to recall the manual office.

At the end of the conversation if the called party 45 replaces his receiver first, a single alternating current impulse is similarly sent to give clearing supervision. When the calling party replaces his receiver or the operator removes her plug, a somewhat prolonged clear-down pulse of alternating current is transmitted over the junction to operate relay AC, which thereupon brings up relays A and C and the latter as before short-circuits relay B. The duration of the releasing pulse is, 50 however, considerably in excess of the slow releasing time of relay B which therefore restores, and at armature *b2* and *b3* opens the loop to the train of automatic switches.

Relay B also at armature *b5* connects the driving magnet SPM of the rotary switch to the common lead which connects with the homing relays S and R common to the whole exchange. The high resistance relay S in the common set operates in series with the magnet, and at armature 55 *s1* brings up relay R which thereupon short-circuits relay S and increases the current in the circuit sufficiently to enable the driving magnet SPM to energize and advance the wiper SPB on to the next contact. Relay S then releases and restores relay R so that the operation continues

automatically until the wiper reaches its home position, where off-normal springs NSP operated from a cam on the shaft again open, and subsequently when the armature *s2* opens after the release of relay R there is no further circuit for 5 relay S and the switch therefore comes to rest in the home position.

Although in the arrangement described the repeater transmits only two kinds of direct current impulses, it will be understood that the invention 10 is not limited to this number since further circuit changes could be controlled by the rotary switch and if necessary, conditions restored for the final trains of impulses to those prevailing initially.

What is claimed is:

1. In a telephone or like system, an incoming line and an outgoing line interconnected through an impulse repeater, means included in said repeater responsive to impulses of a given type received over the incoming line for repeating 20 25 impulses to the outgoing line of a different type, and means in the repeater for varying the character of the repeated impulses independently of the length of individual received impulses, but dependent upon the number of trains of impulses previously received over the incoming line.

2. In combination, an impulse repeater responsive to trains of incoming impulses to repeat trains of outgoing impulses of a given character, means for counting the trains of impulses as they are 30 received and repeated, and means controlled by the counting means for altering the character of the repeated impulses.

3. In combination, an impulse repeater responsive to train of impulses to repeat corresponding 35 trains of impulses of a given character, counting means controlled by the impulse trains handled by the repeater, and means controlled by the counting means for altering the character of the repeated impulses after a predetermined number 40 of trains of impulses have been repeated.

4. In an impulse repeater for repeating a predetermined number of received trains of impulses to effect successive switching operations and for repeating subsequent received impulses to effect 45 incidental control operations, means for repeating the received trains as impulses of a given character, means for counting the trains of impulses as they are repeated, and means controlled by the counting means when it has counted the 50 predetermined number of impulse trains for altering the repeater so that subsequently received impulses are repeated as impulses of a different character, whereby the control operations may be more readily performed.

5. In combination, an impulse repeater responsive to trains of impulses to repeat corresponding 55 trains of impulses of a given character, counting means controlled by the impulse trains handled by the repeater, means controlled by the counting means for altering the character of the repeated impulses after a predetermined number of trains of impulses have been repeated, and means responsive to the receipt of a prolonged incoming impulse for restoring said counting means at the 60 end of such prolonged impulse.

6. In a telephone system, an incoming telephone line extending to an automatic switchboard by way of an impulse repeater, means in the repeater responsive to impulses received over said 70 line for repeating setting impulses to said switchboard, means in said repeater for responding to an answering-supervisory indication and subsequently to a disconnect-supervisory indication transmitted thereto from said switchboard, a 75

slow-operating and slow-releasing relay in said repeater, and means in said repeater responsive to one received supervisory condition for transmitting a supervisory impulse back over the incoming line of a duration governed by the slow-operating characteristic of said relay and responsive to the other supervisory condition for transmitting a supervisory signal back over the incoming line of a duration governed by the slow-releasing characteristic of said relay.

7. In a telephone system, a telephone line extending to a switchboard by way of a repeater, control means in the repeater responsive to the initiation and to the termination of a state of answered supervision controlled through said switchboard, a relay having a slow-operating characteristic and a slow-releasing characteristic, and means operated from the control means on one response thereof to send a supervisory impulse back over said line of a duration con-

trolled by the slow-operating characteristic of said relay and operated from the control means on the other response thereof to send a supervisory impulse back over the said line of a duration controlled by the slow-releasing characteristic of said relay. 5

8. In a telephone system, a telephone line extending to a switchboard by way of a repeater, control means in said repeater arranged and adapted to operate upon the initiation of and to 10 restore upon the termination of a distinct supervisory state imposed on said line through said switchboard, a relay having a slow-responding characteristic, and means operable under the control of said control means at the initiation of 15 and again upon the termination of said supervisory condition to transmit a supervisory impulse over said line of a duration governed by the slow-responding characteristic of said relay.
